US0D1035181S

(12) **United States Design Patent** (10) Patent No.: **US D1,035,181 S**
(45) Date of Patent: ** Jul. 9, 2024

(54) **TOY FOR ANIMALS**

(71) Applicant: **Rong Chen**, Xiamen (CN)

(72) Inventor: **Rong Chen**, Xiamen (CN)

(**) Term: **15 Years**

(21) Appl. No.: **35/518,086**

(22) Filed: **Jul. 28, 2023**

(80) **Hague Agreement Data**

Int. Filing Date: **Jul. 28, 2023**

Int. Reg. No.: **DM/230685**

Int. Reg. Date: **Jul. 28, 2023**

Int. Reg. Pub. Date: **Aug. 18, 2023**

(51) LOC (14) Cl. 30-99

(52) U.S. Cl.

USPC **D30/160**

(58) **Field of Classification Search**

USPC D30/160, 199; D21/460

CPC A01K 15/025; A01K 15/026

See application file for complete search history.
